PROCESS OF MANUFACTURING LIQUID HYDROCARBONS

James R. Rose, Edgeworth, Pa.

Application April 6, 1938, Serial No. 200,359

4 Claims. (Cl. 196—10)

This invention relates to a process for converting normally gaseous hydrocarbon material into normally liquid hydrocarbon material, and has particular reference to the treatment of 5 petroleum refinery gases for the conversion of the same into liquid hydrocarbon material in the nature of motor fuel.

As is well known by those acquainted with this art, the gases resulting from the cracking of oil 10 contain saturates and unsaturates, the proportions of which vary in accordance with the variation in the particular fields from which the crude oils are obtained that are subjected to cracking operations.

15 It is the general purpose and object of my invention to provide a process whereby a higher proportion of the saturates and unsaturates in the aforesaid gases may be converted into liquid hydrocarbon than has hitherto been found possible 20 of accomplishment. In the practice of my process, I make use of a catalyst for the purpose of condensing and polymerizing the gaseous hydrocarbons subjected thereto. While my process is 25 of value, irrespective of the particular kind of catalyst employed, I have found that I am able to effect a maximum recovery of liquid hydrocarbons by the use in such process of the particular catalyst set forth herein.

30 My process is realizable in and through the use of the apparatus illustrated in the drawing, wherein the figure is a flow diagram illustrating my preferred apparatus and showing the relation of the various parts of such apparatus to one another.

35 Describing my process in connection with the aforesaid drawing, 1 denotes a pipe for conducting raw refinery gas to the meter 2, whence it is delivered into a compressor 3, where it is subjected to a pressure of from 100 to 600 pounds 40 per square inch and whence it is delivered to a condenser 4, including a water coil 5. By this treatment, hydrocarbons as heavy as butane, together with small amounts of normally liquid hydrocarbons that are heavier than butane, are 45 condensed and delivered through a pipe 6 into the stabilizer tower 7 having a steam coil 8 in the bottom thereof which is heated to a temperature of approximately 300° F. and which serves to boil off the lighter products, which contact 50 with the condenser 9 at the top of the stabilizer.

This condenser serves to re-condense any of the heavier hydrocarbons that are being carried off by the lighter products, and these heavier hydrocarbons drop to the bottom of the tower, whence they are drawn off into the cooler 10, together with the liquid which has remained in the bottom of the stabilizer. The cooler is provided with the cooling coil 11, and the cooled liquid is delivered therefrom into the final-products receiver 12.

10 The gases from the condenser 4 are delivered through pipes 13 and 15 to a re-cycling meter 16, the pressure of the gases so delivered being suitably reduced by passing through the valve 13a. The gases from the stabilizer 7 are delivered 15 through pipes 14 and 15 to the re-cycling meter 16, the pressure of these gases being suitably reduced by passing through the valve 14a. It is preferred that the gases delivered to the re-cycling meter shall have a pressure not in 20 excess of 5 lbs. per square inch. From the re-cycling meter, the gases are conducted through the pipe 17 to the holder 18.

25 The gaseous mixture in the holder 18 is delivered thence to a compressor 19, where it is subjected to a pressure of from 800 to 1500 pounds per square inch and is delivered thence under such pressure into the cooler 20. By this treatment, the gases are practically completely liquefied, and the liquid, or largely liquid, product is delivered 30 into the liquid holder 21, under the same pressure. The small proportion of unliquefied gases remaining after this treatment may be taken from the top of the holder through a pipe 22 and used for any desired purpose, such as for heating a stove 23 having therein cracking coils 24 to which the liquid from the holder 21 is delivered through pipe 25. In this stove, the liquid delivered from the holder 21 is cracked into 35 a gaseous condition under temperatures of from 800° to 1500° F. The gaseous fluid produced in the cracking coils is delivered through banks of tubular catalyst receptacles 26, 27 and 28, the banks being connected by pipes 29 and 30. It will be noted that the cracked product is caused 40 to traverse the full length of the banks of catalyst tubes in series, passing from the bottoms of the tubes 26 in the first bank to the bottoms of the tubes 27 in the second bank and from the tops of the tubes 27 into the tops of the tubes 28 in 45 50

the third bank. The catalyst which I use in the banks of the tubular receptacles 26, 27 and 28 consists preferably of a mixture of carnotite, phosphate rock, Floridan clay, zinc phosphate and barium chloride, bonded together with commercial fire bond. The ingredients are preferably mixed in the following proportions by weight:

	Parts
10 Carnotite	27
Phosphate rock	27
Floridan clay	27
Zinc phosphate	5
Barium chloride	4
15 Fire bond	10

It will be noted that the catalyst receptacles are contained in a chamber forming an extension of the stove proper, whereby they will be heated efficiently by the products of combustion delivered into the top of the chamber wherein they are located, the products passing off from the bottom of the chamber into a stack 31. By this arrangement, the temperature of the cracked product will not be materially reduced when delivered into the pipe or pipes 30, since the exothermic reaction occurring within the catalyst receptacles compensates for the reduction in temperature of the products of combustion passing in contact therewith.

30 In passing through the catalyst tubes or receptacles, the cracked product is polymerized and converted almost entirely into a hydrocarbon suitable for motor fuel. This hydrocarbon at this stage is in a vaporous condition, and is delivered through one or more pipes 30 into the header 32. From this header, the polymerized material passes through a pipe 33 having an expansion valve 34, which reduces its pressure to approximately 100 lbs. per square inch, being delivered 35 from said valve to a receptacle 35 having a water coil 36 therein, the purpose of the receptacle and coil being to prevent the freezing of the expanding fluid directed through the valve 34. The fluid from the receptacle 35 is delivered into the ballast chamber or collector 37. From the ballast chamber 37, the material is delivered in turn to the separator 38, which is provided with a pipe 38^a for draining water therefrom, and thence through the pipe 39, valve 40 and cooler 41, into the receiver separator 42. The ballast chamber 37, the separator 38 and the receiver separator 42 all cooperate to stabilize the product, enabling material therein which is of an intermediate nature between the liquid and the gaseous state to coalesce and unite with the body of the liquid, the latter two receptacles serving the purpose of enabling the lighter products to boil off in the form of gases and to be carried off by their respective vent lines.

50 The lighter products in 38 are conducted through the pipe 43, pressure reducing valve 44, and flow meter 45 into the vent line 46 which leads from the top of the receiver separator 42 and conveys the gases from the separators 38 and 42 to the re-cycling meter 46, the pipe 46 being also provided with a pressure reducing valve 46^a by which the pressure of the gases from the separators 38 and 42 will be reduced to a pressure 55 preferably not exceeding 5 lbs. before passing through the re-cycling meter.

55 The liquid hydrocarbon collected within the receiver separator is delivered through the pipe 47 and valve 48 into the stabilizer 7, where it is subjected to the same treatment as the butane

and/or other heavy hydrocarbons delivered from the condenser 4, the liquid hydrocarbons from both sources being heated by the steam coil 8. The stabilizer 7 thus serves not only to stabilize the liquid hydrocarbons delivered thereinto from both sources, but also to blend the same.

60 It will be noted that, in the practice of my process, I effect the removal of butane and/or other heavier hydrocarbons (such as pentane and pentene) by pressure and condensation, without recourse to catalyzation; also that the gases from the condenser 4, stabilizer 7, and the stabilizing receptacles 31, 38 and 42 are liquefied by pressure and cooling, the liquid thus produced being cracked under high pressure and this product being largely converted into liquid hydrocarbon by polymerization in the catalyst tubes or receptacles 26, 27 and 28 and by stabilization in the receptacles 31, 38, 42 and 7.

Having thus described my invention, what I claim is:

1. The process of manufacturing liquid hydrocarbons suitable for motor fuel from petroleum refinery gases containing saturates and unsaturates which comprises subjecting the said gaseous material to a pressure of from 100 to 600 lbs. per square inch and to a cooling action, thereby to condense from such gaseous material hydrocarbons as heavy as and heavier than butane; subjecting the gaseous residue to a pressure of 30 from 800 to 1500 lbs. per square inch and to a cooling action, thereby to liquefy the said residue; subjecting the residue while under the said pressure to a cracking temperature of from 800° to 1500° F.; subjecting the resultant material while 35 under the said pressure to a catalyst to facilitate the polymerization thereof, thereby to form normally liquid hydrocarbon material, said catalyst comprising a mixture of the following ingredients in approximately the following proportions: 40

	Parts
Carnotite	27
Phosphate rock	27
Floridan clay	27
Zinc phosphate	5
Barium chloride	4
Fire bond	10

2. The process of manufacturing liquid hydrocarbons suitable for motor fuel from petroleum 50 refinery gases containing saturates and unsaturates which comprises subjecting the said gaseous material to a pressure of from 100 to 600 lbs. per square inch and to a cooling action, thereby to condense from such gaseous material hydrocarbons as heavy as and heavier than butane; subjecting the gaseous residue to a pressure of 55 from 800 to 1500 lbs. per square inch and to a cooling action, thereby to liquefy the said residue; subjecting the residue while under the said pressure to a cracking temperature of from 800° to 1500° F.; subjecting the resultant material while under the said pressure and temperature to a catalyst to facilitate the polymerization thereof, thereby to form normally liquid hydrocarbon material, 60 said catalyst comprising a mixture of the following ingredients in approximately the following proportions:

	Parts
Carnotite	27
Phosphate rock	27
Floridan clay	27
Zinc phosphate	5
Barium chloride	4
Fire bond	10

and separating normally gaseous material from said liquid hydrocarbon.

3. The process of manufacturing liquid hydrocarbons suitable for motor fuel from petroleum refinery gases containing saturates and unsaturates which comprises subjecting the said gases to a pressure of from 800 to 1500 lbs. per square inch and to a cooling action, thereby to liquefy the said gases; subjecting the resultant liquid while under the said pressure to a cracking temperature of from 800° to 1500° F.; subjecting the resultant material while under the said pressure to a catalyst to facilitate the polymerization thereof, thereby to form normally liquid hydrocarbon material, said catalyst comprising a mixture of the following ingredients in approximately the following proportions:

Parts	
Carnotite	27
Phosphate rock	27
Floridan clay	27
Zinc phosphate	5
Barium chloride	4
Fire bond	10

25 4. The process of manufacturing liquid hydro-

carbons suitable for motor fuel from petroleum refinery gases containing saturates and unsaturates which comprises subjecting the said gases to a pressure of from 800 to 1500 lbs. per square inch and to a cooling action, thereby to liquefy the said gases; subjecting the resultant liquid while under the said pressure to a cracking temperature of from 800° to 1500° F.; subjecting the resultant material while under the said pressure and temperature to a catalyst to facilitate the polymerization thereof, thereby to form normally liquid hydrocarbon material, said catalyst comprising a mixture of the following ingredients in approximately the following proportions:

Parts	15
Carnotite	27
Phosphate rock	27
Floridan clay	27
Zinc phosphate	5
Barium chloride	4
Fire bond	10

27

27

27

5

4

20

10

and separating normally gaseous material from said liquid hydrocarbon.
